UNITED STATES PATENT OFFICE.

BURT A. SMITH, OF TACOMA, WASHINGTON.

REIN-HOLDER.

SPECIFICATION forming part of Letters Patent No. 721,754, dated March 3, 1903.

Application filed December 16, 1902. Serial No. 135,451. (No model.)

To all whom it may concern:

Be it known that I, BURT A. SMITH, a citizen of the United States, residing at Tacoma, in the county of Pierce and State of Washington, have invented a new and useful Rein-Holder, of which the following is a specification.

My invention relates to improvements in devices for holding reins in which the reins are clamped to the dashboard or other part of the vehicle; and the objects of my invention are to simplify and cheapen the device and to provide means to prevent the reins from being removed from the clamp except by first pulling the reins, and thus loosening the clamp. I attain these objects by the mechanism illustrated in the accompanying drawings, in which—

Figure 1 is a vertical section of the holder through the clamping-cylinder, and Fig. 2 is a plan showing also one of the clamping-cylinders in horizontal section.

Similar letters of reference refer to similar parts throughout both views.

The base-plate A is fastened, by means of screws, clamps, or other suitable devices, to the vehicle and is provided with two projections B on its upper side, through which pass the pivot-bolts C, which fasten the rollers or cylinders D to the plate A. These rollers do not touch plate A, but rest on the projections B and turn about the pivots C.

The rollers D are cylindrical in shape and are mounted eccentrically on the pivot C. Their cylindrical sides are smooth—that is, without serrations thereon. They are provided with rims E, projecting over the cylindrical sides. These rims E may or may not pass entirely around the rollers. I find that in some cases it is advisable to cut this rim away at that portion of each rim opposite to each other when the clamp is in its "open" position, being careful not to remove that portion of each rim opposite to each other when the clamp is in its "closed" position, as shown in the drawings.

The position of the projections B is such that if the cylinders were separately swung about the pivot C they would pass over the line midway between the projections B. The

stops F are placed to prevent the cylinders C from rotating beyond the above midway line.

The springs G are wound around the projections B, one end passing through a hole in the plate A and the other end passing through a hole in the cylinders D. The springs G tend to turn the cylinders D about the pivots C into the closed position—that is to say, toward each other.

My device is put in operation as follows: The reins H are pulled in the direction opposite to the arrow in Fig. 2—that is, away from the horse—until they are almost as tight as it is desired to leave them. Then they are placed so that they press against the rims E between the two cylinders D and are then pulled tighter. This motion draws the cylinders back and separates them, so that the reins H are placed between them and are dropped. The tension on the horse side now pulls the reins H in the direction of the arrow in Fig. 2 and draws the cylinders D with them, thus closing the space between them and firmly clamping the reins. The harder the horse pulls the firmer the clamp holds the reins. Sometimes there is a tendency for the reins to slip upward; but the rims E prevent their getting out from the clamp.

I am aware that prior to my invention rein-holders have been made with eccentrically-mounted cylinders.

What I claim, therefore, as my invention, and desire to secure by Letters Patent, is—

In a rein-holder, the combination of a base-plate two projections thereon adapted to support the cylinders, pivots attached to said projections, two cylinders eccentrically mounted on said pivots, and having smooth sides, rims projecting over said sides, springs adapted to turn the cylinders, and stops adapted to limit the motion thereof, substantially as and for the purpose described.

In testimony whereof I have signed my name to this specification in the presence of two subscribing witnesses.

BURT A. SMITH.
